(57) **CLAIM**

The ornamental design for a monitor for computer, as shown and described.

DESCRIPTION

1. Monitor for computer

1.1: Perspective

1.2 : Rear perspective

1.3: Front

1.4: Back

1.5: Left

1.6: Right

1.7: Top

1.8: Bottom

The broken lines indicate portions of the article that form no part of the claimed design.

1 Claim, 8 Drawing Sheets(56)
